[57] CLAIM

The ornamental design for a multiple battery charging unit or similar article, substantially as shown and described.

DESCRIPTION

FIG. 1 is a top perspective view of a multiple battery charging unit or similar article showing our new design;

FIG. 2 is a side elevational view thereof;

FIG. 3 is a rear elevational view thereof;

FIG. 4 is a bottom plan view thereof; and

FIG. 5 is a top perspective view of a modified embodiment of the multiple battery charging unit or similar article illustrated in FIG. 1 it being understood that the undisclosed sides are the same in appearance as that shown in FIGS. 2-4.
